DRAFT CONTROL

Frank R. Hiner, Grand Rapids, Mich., assignor
to Teesdale Manufacturing Company, Grand
Rapids, Mich., a corporation of Michigan

Application June 21, 1935, Serial No. 27,741

5 Claims. (Cl. 236—45)

The present invention relates to draft controls, or means for controlling or checking the draft of fluid through pipes, flues and the like, particularly furnace smoke pipes; and its object is, generally, to provide means and devices of that character improved as hereinafter described; and more particularly, to provide such a control automatically operated by the draft itself; and further, to provide such a control which may be 10 nicely adjusted for operation by a predetermined degree of draft; and further, to provide such a control whereby the draft through a furnace may be maintained approximately constant and at a predetermined degree, although the draft 15 through its smoke pipe or chimney may fluctuate considerably; and further, to provide in combination with such a control, means for creating a forced draft during predetermined conditions; and further, to provide certain specific means for 20 carrying out such objects.

These and any other and more specific objects hereinafter appearing are attained by and the invention finds preferable embodiment in, the structure and mechanism particularly described 25 in the body of this specification and illustrated by the accompanying drawings, in which:

Figure 1 is an elevational view of portions of a furnace and of a chimney with a smoke pipe extending therebetween provided with my draft 30 control;

Figure 2 is an elevational side view of said control, its damper in position partially closing the smoke pipe which is shown in transverse section taken on line 2—2 of Figure 1;

Figure 3 is a view similar to Figure 2 (somewhat enlarged) showing the damper in position fully opening the smoke pipe which is shown in transverse section taken on line 3—3 of Figure 4;

Figure 4 is a top plan view thereof;

Figure 5 is a sectional view of the same taken on line 5—5 of Figure 3;

Figure 6 is an elevational view of the same, partially sectioned on line 6—6 of Figure 3;

Figure 7 is an elevational view similar to Figure 45 1, and showing draft-forcing means;

Figure 8 is an elevational side view (enlarged) of a portion of said control and electrical means for initiating the draft-forcing means;

Figure 9 is an elevational front view of a portion thereof, partially sectioned on line 9—9 of Figure 8.

In these drawings (Figures 1 and 7) my draft control is shown applied to the smoke pipe 2 leading from a furnace 3 to the chimney 4, although 55 this control may be applied to various pipes, flues

or passages to control fluid flow therethrough. In the illustrated application, the draft control, indicated generally 1, comprises a hollow member or body made of sheet metal or the like and having flat parallel opposite walls 5, 6 and curved 5 walls 7, 8 connected thereto, the walls 5, 6 extending at right angles to the smoke pipe's axis. In this relation said body is secured to the smoke pipe by suitable means as by one or more threaded bolts 9 extending through the outwardly 10 turned flanges 10 of the mutually adjacent ends of the walls 7, 8, these walls being curved over the smoke pipe to embrace one side 11 thereof and the parallel walls 5, 6 having their free inner edges 12 concave correspondingly with the smoke 15 pipe's form to embrace the opposite side 13 thereof, in which position said body is tightly clamped on the smoke pipe by turning down the nuts 14 of said bolts.

Said body contains an oscillatory damper 20 made of sheet metal or the like, comprising a flat vane portion 15 extending parallel with the walls 5, 6 and an arm portion 16 pivotally mounted at 17 on said body so that the damper may be swung to carry the vane portion inwardly-outwardly of 25 the smoke pipe through an arcuate slot opening in the side thereof, or through the gap 18 between adjacent lengths or sections 19 thereof as shown, said lengths being overlapped and connected by the body's walls 7, 8 and said gap 30 closed thereby except at the smoke pipe's side 13 through which the vane portion is moved.

Said arm portion's lateral edges 22 are in approximate contact with the inner surfaces of the walls 5, 6 and the arm's free inner end 25 in 35 approximate contact with the inner surface of the wall 7 in the damper's swinging movement.

It will be seen that said hollow body member forms a chamber open at 23 to atmosphere and open through said gap into the smoke pipe, this 40 chamber forming a channel along which the arm portion 16 moves as a closure therefor.

It will be seen that the draft through the smoke pipe in the direction of the arrows (i. e. from the furnace to the chimney) diminishes, to a greater 45 or less degree depending on the force of the draft, the fluid pressure in said chamber thus causing the damper to swing inwardly by reason of relatively greater pressure on the closure arm's outer side, and that this movement carries the vane 50 portion 15 through said gap 18 into the smoke pipe, to a correspondingly greater or less degree depending on this draft force, thus diminishing the cross-sectional area of the smoke passage and checking and controlling the draft.

To adjust the desired movement of the damper to the force of the draft, the arm portion 16 has an outwardly extending rod 28 along which a block 29 is slidable to positions clamped thereon by the set screw 30, and a counterweight 31 has a screw shank 32 threaded in this block, so that the weight may be moved to a nicely adjusted position.

Inasmuch as the draft through the chimney itself fluctuates greatly and suddenly by reason of varying rarefaction of gases therein or changing winds which create a suction from its mouth, and in order to maintain the draft through the furnace itself as constant as possible, my control 5 is made essentially a part of that portion or section of the smoke pipe which extends between the furnace and the partially closed vane portion 15 rather than a part of the smoke pipe which extends beyond said vane. To effect this 10 end, the said vane portion is located adjacent that lateral edge 27 of the closure arm which is remote from the furnace, so that the body member's said chamber or channel opens into the smoke pipe between the furnace and said vane 15 portion.

If the counterweight 31 be adjusted to the desired position (say to that shown in Figure 3 wherein the smoke pipe is entirely open), the draft through the furnace will not be diminished 20 by the draft through the chimney unless and until the chimney draft increases sufficiently to draw the closure arm 16 inwardly thus moving the vane portion 15 inwardly to check the draft; and the draft through the furnace will not be 25 materially affected by the fluctuating draft through the chimney unless such fluctuations become strong enough and sufficiently long continued to move the vane portion inwardly or weak enough to permit it to move oppositely. 30 It will thus be seen that changes in the draft through the furnace do not occur by reason of comparatively slight fluctuations in the chimney draft nor immediately thereafter, for my control does not respond to such fluctuations nor immediately the same occur, the gases in the chimney 35 being elastic and of varying rarefaction.

A spring 48 cushioning the falling movement of the closure arm 16, and a rigid stirrup 49 in which the pivot bolts 17 are mounted, are shown 50 in Figures 5 and 6.

It will be seen that inasmuch as the damper is pivotally mounted on the axis 17 which is outside the smoke pipe and on the outer side of closure arm (as shown in Figures 2 and 3), this pivotal mounting is not fouled by smoke or soot in 55 the pipe nor corroded by gases therein.

A rotary fan indicated at 33 (Figure 7) having a discharge pipe 34 venting into the smoke pipe may be employed for creating a forced draft 60 therein. This fan's motor indicated at 35 in an electric circuit 36 is energized by closing a mercury switch of the ordinary form, shown in Figures 8 and 9, in which the mercury tube 37 whose mounting 38 pivoted at 39 is suddenly 65 turned to open or closed positions by the spring 40 connecting said mounting with the actuating lever arm 41 pivoted at 42. This arm is connected by a link 43 with the damper's rod 28 which has a wrist pin 44 engaging slidably in the link's 70 slot 45.

The switch is operated by the damper in the following manner: Assuming the damper to be open, its vane portion 15 withdrawn from the smoke pipe, the damper's rod 28 will assume the 75 position shown in solid lines in Figure 8; assum-

ing that the chimney is cold, no draft or insufficient draft therein, the lever arm 41 may be manually turned to the position seen in said view whereby the switch is closed, the motor energized and a forced draft thereby created by the 5 fan. As the draft increases, the closure arm 16 is drawn up as hereinbefore explained checking the draft; and the rod 28 falling causes its wrist pin 44 to strike the bottom end 46 of slot 45 thereby opening the switch and stopping the motor 10 and the fan. If the draft then diminishes sufficiently so that the closure arm 16 falls, its rod 28 rises until the wrist pin strikes the upper end 47 of said slot again closing the switch.

It will be seen that this fan and operating 15 switch are employed for extreme draft conditions, and that during the usual operation of my draft control the wrist pin 44 oscillates along the slot 45 without striking either end thereof.

It will also be seen that when the vane portion 20 15 is in partially closed position shown in Figures 1 and 2, the direction of the draft is somewhat deflected from the closure arm 16 by the vane's inner edge 26 thus tending to relieve the pressure on the inner side of said closure 25 arm and causing the vane portion to swing farther inwardly, said vane portion being located adjacent that lateral edge of the closure arm which is remote from the furnace.

The invention being intended to be pointed out 30 in the claims, is not to be limited to or by details of construction and arrangement of the particular embodiment thereof illustrated by the drawings or hereinbefore described.

I claim:

1. In a draft control for a pipe comprising sections spaced endwise to provide a gap therebetween; a hollow body member secured to said sections and comprising parallel sides extending in a direction transversely of the sections and having edges fittingly engaging one side thereof, and curved sides one of which fittingly engages the opposite sides of said sections, said member forming a channel of substantial width in the pipe's axial direction open at spaced points to the atmosphere and into said gap; a damper oscillatingly-swingably mounted on an axis parallel with the pipe, comprising a closure portion for the channel oscillatingly movable therealong between said points by relative degrees of fluid 50 pressure on its opposite sides, the damper including also a vane portion movable through said gap inwardly of the pipe by increased draft therein and oppositely by decreased draft therein, the vane portion being connected to the closure portion adjacent the lateral edge thereof 55 which is remote from the inlet end of the pipe.

2. A draft control for a pipe having an opening extending through and partially around its side, comprising: a hollow body member extending radially from said side having side walls disposed at approximately right angles to the pipe and forming a channel open at spaced points to the atmosphere and into the pipe's opening respectively; a control member in the body member having a damper vane portion extending in a direction at approximately right angles to the pipe's axis and adapted to be moved through the pipe's opening, and having also an arm portion extending laterally parallelly with said axis and being swingably mounted on an axis parallel with the pipe's axis for oscillatory movement in and along the channel between said points and forming a closure for the channel prohibiting entrance of air from the atmosphere to said pipe, 75

said control member being movable inwardly by the atmospheric pressure relatively greater than fluid pressure in the pipe to carry the vane portion inwardly of the pipe and movable outwardly by fluid pressure in the pipe relatively greater than the atmospheric pressure to carry the vane portion outwardly of the pipe.

3. A draft control for a pipe having an opening extending through and partially around its side, comprising: a hollow body member extending radially from said side having side walls disposed at approximately right angles to the pipe and forming a channel open at spaced points to the atmosphere and into the pipe's opening respectively; a control member in the body member having a damper vane portion extending in a direction at approximately right angles to the pipe's axis and adapted to be moved through the pipe's opening, and having also an arm portion extending laterally parallelly with said axis and being swingably mounted on an axis parallel with the pipe's axis for oscillatory movement in and along the channel between said points and forming a closure for the channel prohibiting entrance of air from the atmosphere to said pipe, said control member being movable inwardly by the atmospheric pressure relatively greater than fluid pressure in the pipe to carry the vane portion inwardly of the pipe and movable outwardly by fluid pressure in the pipe relatively greater than the atmospheric pressure to carry the vane portion outwardly of the pipe.

4. A draft control for a pipe having an opening through its side, comprising: a hollow body member extending radially from said side forming a channel open at spaced points to the atmosphere and into the pipe's opening respectively; a control member in the body member hav-

ing a damper vane portion adapted to be moved through the pipe's opening and having also an arm portion at approximately right angles to the vane portion and swingably mounted on an axis parallel with the pipe for oscillatory movement in and along the channel between said points and forming a closure for the channel prohibiting entrance of air from the atmosphere to said pipe, said control member being movable inwardly by the atmospheric pressure relatively greater than fluid pressure in the pipe to carry the vane portion inwardly of the pipe and movable outwardly by fluid pressure in the pipe relatively greater than the atmospheric pressure to carry the vane portion outwardly of the pipe.

5. A draft control for a pipe having an opening through its side, comprising: a hollow body member extending radially from said side forming a channel open at spaced points to the atmosphere and into the pipe's opening respectively; a control member in the body member having a damper vane portion adapted to be moved through the pipe's opening and having also an arm portion at approximately right angles to the vane portion and swingably mounted on an axis parallel with the pipe for oscillatory movement in and along the channel between said points and forming a closure for the channel prohibiting entrance of air from the atmosphere to said pipe, said control member being movable inwardly by the atmospheric pressure relatively greater than fluid pressure in the pipe to carry the vane portion inwardly of the pipe and movable outwardly by fluid pressure in the pipe relatively greater than the atmospheric pressure to carry the vane portion outwardly of the pipe.
